UNITED STATES PATENT OFFICE.

ARTHUR TINDALL REYNOLDS, OF NEW YORK, N. Y.

UPHOLSTERING.

1,349,629.

Specification of Letters Patent. Patented Aug. 17, 1920.

Application filed January 6, 1919. Serial No. 269,830.

To all whom it may concern:

Be it known that I, ARTHUR TINDALL REYNOLDS, a subject of the King of Great Britain, and resident of 351 First St., city of New York, State of New York, in the United States of America, have invented certain new and useful Improvements in Upholstering, of which the following is a specification.

10 The invention relates to improvements in upholstering as described in the present specification and illustrated in the accompanying drawings that form a part of the same.

15 The invention consists essentially of the novel means employed for detachably securing the padding in its receptacle.

The objects of the invention are to provide a means whereby the filling of a mattress, chair back, lounge seat or any other upholstered article may be readily removed to permit of disinfecting or for other reasons, to provide a shaped receptacle whereby persons other than those skilled in the 25 art may refill or repair articles of this nature, to permit of the ordering of completed receptacles by mail to be filled on arrival and generally to provide an article of the class described which will be inexpensive to manufacture, durable and efficient.

In the drawings Figure 1 is a perspective view of a mattress with the various inclosing flaps partly opened up.

35 Fig. 2 is a longitudinal sectional view through a mattress.

Fig. 3 is a side view showing the flaps completely opened out.

40 Fig. 4 shows the invention as applied to a chair back.

Like numerals of reference indicate corresponding parts in the various figures.

Referring to the drawings the envelop or receptacle 1 which may be constructed of 45 tapestry or any other desired material is preferably sealed permanently on all of its sides but one and is divided into a plurality of sections by means of partitioning members 2 so that the padding material 3 from 50 a particular section may be removed without interfering with the remaining sections.

One side of the receptacle is provided with a projecting flap 4 substantially equal 55 in width to the thickness of said receptacle

when stuffed, said flap being provided along its edge adjacent to the corresponding side of the receptacle with catches 5 adapted to be engaged by fasteners 6 secured along the inner side edge of a flap 7 which is secured to the opposite side of said receptacle. 60

The ends 8 of the receptacle are provided with short flaps 9 having fasteners 10 thereon adapted to engage corresponding catches 10^a on the outer side of the flap 7, 65 so that when the flap 7 is drawn up over the flap 4 and the fasteners 6 are secured to the catches 5 and the flaps 9 are secured to said flap 7 the padding will be securely held in position within said receptacle. 70

To provide further security a flap 11 secured to the side of the receptacle from which the flap 4 extends is provided, said flap 11 being of sufficient size to completely cover the flaps 4 and 7 and being provided 75 around its inner edge with fasteners 12 adapted to be secured in catches 13 around the outer side of said flap 7.

It will thus be seen that when it is desired to disinfect the padding or to wash the 80 envelop it is only necessary to unfasten the various flaps and remove the padding. As the receptacle is divided into a plurality of small compartments it will be found an easy matter to replace the padding evenly 85 and thus reinstate the article to its former perfect form.

This method of construction will be found to be of great advantage to persons living in the country or a considerable distance from the store and who already have the material for padding as they merely have to order the required size of receptacle and same can be sent them by post complete for 90 filling. 95

This mode of construction has been illustrated in the drawings only in connection with mattresses and chair backs but it must be understood that the same may apply to chair arms, curved or otherwise, lounge seats, vehicle seats and in fact any and all stuffed articles merely by constructing the various parts to the required shape. 100

What I claim is:

In upholstering, a padding receptacle of 105 substantially mattress shape and having one of its side edges cut away forming an opening for the insertion of padding, said receptacle being divided into a plurality of compartments common to said opening, a 110

flap projecting from one of the sides of said receptacles and adapted to fold over said opening, a flap secured to the opposite side of said receptacle and adapted to fold over 5 the aforesaid flap and to be secured thereto, end flaps adapted to be secured to the last mentioned flap and an inclosing flap secured to one of the sides of said receptacle and folding over all of the aforesaid flaps

and adapted to be secured to the second 10 mentioned flap.

Signed at Toronto, Ont. this 13th day of December, 1918.

ARTHUR TINDALL REYNOLDS.
